UNITED STATES PATENT OFFICE.

HERMAN BENMOSCHE AND MOSES BENMOSCHE, OF NORFOLK, VIRGINIA,
ASSIGNORS OF ONE-HALF TO CHARLES FRIEDLANDER, OF NORFOLK,
VIRGINIA.

RATCHET-DRILL.

SPECIFICATION forming part of Letters Patent No. 714,437, dated November 25, 1902.

Application filed August 30, 1901. Serial No. 73,783. (No model.)

To all whom it may concern:

Be it known that we, HERMAN BENMOSCHE and MOSES BENMOSCHE, citizens of the United States of America, residing at Norfolk, in the 5 county of Norfolk and State of Virginia, have invented certain new and useful Improvements in Ratchet-Drills, of which the following is a specification.

Our invention relates to ratchet-drills, and 10 has for its object to produce such a device that will rotate a head-stock, clutch, or other tool-holder in which a drill, screw-driver, bolt, nut, or other articles requiring a rotary motion may be placed and motion imparted 15 thereto by the reciprocation of the handle. This rotary motion is imparted to the head-stock, clutch, or other tool-holder by each stroke of the handle, thus causing the tool held therein to revolve in one continuous 20 path.

Another object of our invention is to provide a ratchet-drill with an automatic feed which will hold the bit, screw-driver, or other tool in contact with the article upon which 25 the tool is working and will cause the same to bite or drive an equal amount at each stroke of the handle.

For the attainment of these objects and for such other purposes as may hereinafter appear 30 our invention consists, in brief, in certain details of construction, arrangement, and combination of parts, the novel features of which will be fully described, and specifically pointed out in the claims.

35 While we have shown in the accompanying drawings and described in the specification certain component and coöperative parts which we deem sufficiently improved and operative to carry out the fundamental principles herein incorporated, we do not confine ourselves to the exact details of construction, as various minor changes may be made without sacrificing any of the advantages of this invention.

45 In the drawings forming a part of this specification, Figure 1 is a top plan view. Fig. 2 is a side elevation showing the arrangement of the automatic feed. Fig. 3 is a similar view illustrating the arrangement and construction of the opposite side. Fig. 4 is sec-

tional view of the automatic feed-nut and shaft upon which it travels.

Referring by numerals to the drawings, 1 represents the handle, having mounted therein a shaft 2, carrying oppositely-disposed cogs 55 3, which mesh with semicircular cog-faces 4, arranged upon a slotted block 5. The block is pivoted to the end of the handle by a shaft 6, one end of which projects out at right angles to the block and is provided with a cog 60 7 and a ratchet 8, which are keyed or formed together and loosely mounted upon the said shaft. This shaft is further provided with a sliding stop 9, the object of which will be hereinafter explained. 65

The function of the cogs 3, which mesh with the semicircular cog-faces 4, is to lend rigidity to the implement and at the same time allow the handle to work freely on its pivot-shaft 6 in the block 5. 70

Journalized in the free end of the slotted block is a hollow shaft 10, one end of which is provided with a head 11 for the reception of a tool or other article and the other end projects out parallel with the shaft 6. The 75 shaft 10 is externally screw-threaded, as shown at 12, and is adapted to receive an elongated feed-nut 13, having a central rod 13', adapted to engage the hollow shaft, and a head provided with two points 14, adapted 80 to engage the article upon which the drill is braced, and thereby prevent the nut from turning. This nut is further provided with a beveled slot 15, adapted to receive the tongue 16, upon the face of the sliding stop 85 9, thereby holding the shaft 6 in a rigid position and preventing any movement of the block 5, in which said shaft is secured. It will be readily understood that if such a construction is desired the beveled slot 15 and 90 the tongue 16 may be dispensed with and the elongated feed-nut formed with flat sides and the stop provided with a loop adapted to fit snugly over the nut, thereby accomplishing the same result, or any other desired manner of locking the feed-nut and shaft 6 together may be employed. 95

The shaft 10 is rotated by a ratchet 17, which is keyed thereupon between the slotted ends of the block and is controlled by the 100

spring-actuated pawl 18, mounted upon the handle. It is further rotated by a cog 19, mounted thereupon, which meshes with and is adapted to be driven by the cog 7, loosely mounted on the shaft 6 and keyed to or formed with a ratchet 8, which is controlled by the spring-actuated pawl 20, mounted upon the handle.

It will be readily seen that when the drill 10 is placed in position the block 5 is held rigid by the two points 14 on the feed-nut, which bite into the article upon which the drill is braced, the feed-nut being locked to the shaft 6. The block 5 being held in a rigid position, 15 the shaft 10 is made to revolve by the ratchet-wheel 17, which is controlled by the pawl 18 on the forward motion of the handle and is caused to continue in its revolutions when the handle is moved backward by the pawl 20, which controls the ratchet 8, thereby controlling the cog 7, which is keyed thereto, the cog 7 meshing with and driving the cog 19, keyed upon the rotary shaft.

What we claim as new, and desire to secure 25 by Letters Patent, is—

1. In a ratchet-drill, a slotted block, a rotary shaft journaled in said block having a head upon one end and a feed-nut upon the other, two points upon the free end of the 30 feed-nut, a stationary shaft mounted in said block, a handle pivoted to said stationary shaft, cogs upon the handle engaging semi-circular cogs upon the block, means for locking the stationary shaft and feed-nut together, 35 a ratchet keyed upon the rotary shaft, a pawl mounted upon the handle engaging the ratchet upon the rotary shaft, a cog keyed upon the rotary shaft, a cog loosely mounted upon the stationary shaft, meshing with the 40 cog upon the rotary shaft, a ratchet formed upon the cog mounted on the stationary shaft, a pawl mounted upon the handle engaging the ratchet upon the stationary shaft, substantially as shown and described.

2. In a ratchet-drill, a handle pivoted in a 45 slotted block upon a stationary shaft, the said handle having a shaft mounted therein, keyed upon which are oppositely-disposed cogs, semicircular cogged faces upon one end of the block engaging the cogs upon the handle, a rotary shaft journaled in the free end of the slotted block, of a head upon one end of said rotary shaft, an automatic feed upon the other, a ratchet keyed upon the rotary shaft in the slotted block, a spring-actuated 50 pawl upon the handle adapted to engage and to control the ratchet upon the rotary shaft, a cog keyed to the rotary shaft, meshing with the cog on the stationary shaft, a ratchet formed upon the cog upon the stationary 55 shaft, and a pawl upon the handle for controlling the same, substantially as shown and described.

3. In a ratchet-drill, a handle pivoted upon a stationary shaft in a slotted block, semicircular cog-faces upon the end of the slotted block, engaging cogs keyed upon a shaft in the handle, a revolving shaft mounted in the free end of the slotted block, the said revolving shaft having a head upon one end, and 60 an elongated feed-nut upon the other, a ratchet mounted upon the said revolving shaft in the slotted block, a pawl upon the handle for controlling the said ratchet, a cog keyed to the revolving shaft, said cog meshing with the cog loosely mounted upon the stationary shaft, a ratchet keyed to or formed as a part of the cog upon the stationary shaft, and a pawl upon the handle adapted to engage the ratchet and thereby controlling the 65 same, and means for locking the stationary shaft and feed-nut together, substantially as shown and described.

HERMAN BENMOSCHE.
MOSES BENMOSCHE.
